DRAFT REGULATOR

Rene M. Vidalie, Port Washington, N. Y., assignor to Preferred Utilities Company, Inc., New York, N. Y., a corporation of Delaware

Application March 3, 1936, Serial No. 66,918

17 Claims. (Cl. 236—45)

This invention relates to automatic draft regulators and has particular reference to that type wherein counterbalancing weights may be adjusted to insure a substantially constant predetermined draft on a boiler regardless of outside weather conditions. Such regulators maintain this constant draft by mixing more or less outside air with the stack gases as the stack pull is increased or decreased due to changes in atmospheric conditions. This results in an even pull on the fire box of the boiler regardless of outside conditions.

An object of the invention is to insure the automatic maintenance of such a constant draft in large boiler plants where the economy produced thereby is of great importance. This is accomplished by my improved regulator which is capable of exceedingly fine adjustment by means of a series of counterbalancing weights so arranged and constructed that the mass of the regulating mechanism may be delicately poised on its pivotal mounting and the other adjustments subsequently made to produce and maintain the desired draft under existing conditions.

Other objects and meritorious features of the invention will become apparent from the following specifications taken in conjunction with the drawings, wherein:

Figure 1 illustrates my improved regulating mechanism somewhat diagrammatically in association with a damper door;

Figure 2 is an elevation of the improved regulating mechanism per se;

Figure 3 is a section along line 3—3 of Figure 2;

Figure 4 is a section along line 4—4 of Figure 2;

Figure 5 is a front elevation of one of the variable weight supports;

Figure 6 is a section through the same support diagrammatically showing weights positioned thereby, and

Figure 7 is a perspective of one of the interchangeable weights which may be used with any one of various weight receptacles associated with the regulating mechanism.

Referring now to Figure 1, the improved regulator is shown in conjunction with a box or cabinet 10 having an opening 12 in the front to receive a door 14 and an opening 16 in the back to guide the air to the breeching or stack of the boiler. A throat 18 may be secured by flanged joints 20 around the rear opening of the cabinet where it is not possible to fasten the cabinet directly to the breeching or stack. The door 14 is

arranged to swing inwardly only about a horizontal pivot 22 to which the bottom of said door is secured in any suitable fashion.

The regulating mechanism comprises an element having a circular periphery and adapted to be secured to the outer face of the door 14 in such manner that its rotative center is substantially coincident with the door pivot 22, which element is provided with a plurality of variable balancing weights which may be so adjusted that the said door provides an opening accurately variable to admit a variable amount of air in accordance with the tendency of the draft to change due to outside weather conditions.

The regulator has been illustrated in the form of a sector-like element composed of radial arms 24 and 26 and their included arc 28. While the included arc 28 is a true arc throughout, the radial arms 24 and 26 do not constitute true radii thereof for reasons to be brought out more clearly hereinafter.

For purposes of illustration this sector-like element has been shown formed of T-shaped stock comprising a central web section 30 and an outer peripheral flange 32. Projections 34 are arranged at spaced intervals on one side of the web 30 inside flange 32. These projections may be integral with the sector-like element and extend throughout the major portion of its arc. They are preferably provided with consecutive numerals as indicated at 36. A radial arm 38 is pivoted at one end to stud 40 which is located at the joinder of the two radial arms 24 and 26. The arm is shown as pivoted by means of a bolt 42 which extends through slot 44 in the arm. The arm must be pivoted through such a lost motion connection as the slot provides because the outer end thereof is adapted to swing around the periphery of the true arc of the sector-like element but its pivotal point is not at the true center thereof.

The other end of arm 38 is bifurcated, one portion 46 being offset from the plane of the arm and adapted to swing across the smooth face of the web 30 and the other being threadedly apertured to receive a small hand wheel 48 which may be manually manipulated to cooperate with the projections 34 to fixedly position the said arm 38 at any point in its swinging movement.

A weight 50 is slidably positioned upon arm 38 and provided with a threaded aperture adapted to receive another small manually operable hand wheel 52 which functions to fixedly position the said weight at any point in its sliding movement along the arm 38. The said arm 38 may be pro-

vided with a series of consecutively numbered notches 54 for reference purposes.

A cylindrical weight receptacle 56 is fixedly positioned in any desired manner to the sector-like element at the joinder of radial arm 26 with the true arc thereof. This receptacle is provided with a series of splines 58 extending along the wall of the cylinder at spaced intervals for the purpose of properly centering a series of removable weights 60. As indicated in Figure 7, these weights are of substantially conventional design and are provided with a lower annular groove 62 which is adapted to cooperate with the upper annular bead 64 of another weight to retain a series of weights in proper alignment. A slot 66 extends diametrically through a substantial portion of each weight.

The open end of cylindrical weight receptacle 56 is provided with a cover plate 68 centrally apertured to receive a headed bolt 70 which is adapted to extend through the slots 66 in the weights 60 to assist in positioning the same within the receptacle. This bolt 70 is threaded into the base of the receptacle as indicated at 72 to position the cover plate and retain the weights therein. It is clear that the number of weights positioned in the receptacle may be varied as desired by simply removing the cover plate.

A second weight receptacle is fixedly secured to the arc of the sector-like element at substantially the point where that radius of the true arc extending parallel to radial arm 24 intersects the same. The center of mass of this particular weight should be substantially in the plane of door 14. This receptacle is here indicated in the form of a hollow dumbbell provided with a centrally apertured restricted portion 74 and two enlarged end receptacle portions 76 and 78. The dumbbell receptacle is secured to the face of door 14. This receptacle is here indicated in the form of a hollow dumbbell provided with a centrally apertured restricted portion 74 and two enlarged end receptacle portions 76 and 78. The dumbbell receptacle is secured to the face of door 14 by means of a strap 80 which may be secured to or made integral with the restricted portion 74 of the receptacle. The enlarged heads of this dumbbell receptacle may be constructed in the same manner as the weight receptacle 56, hitherto described, and weights 60 have been indicated only diagrammatically. The cover plates 82 and 84 are positioned by means of a rod 86, threaded at each end, extending through the slots in the weights and held in place by nuts 88.

A strap 90 is secured to the outer arcuate face of flange 32, as by means of a series of rivets 92, at a point above where a plane perpendicular to door 14 and passing through the center of the sector arc, or door pivot, would, if extended, intersect the said arc. A support 94 adapted to receive weights 60 is positioned in any suitable fashion at the end of the depending strap and a hook 96 is provided at the extremity of the assembly for a reason to be more clearly brought out hereinafter.

Radial arm 24 is provided with a series of spaced laterally extending rigid straps 98, secured to or made integral with the said arm, by which the heretofore described regulating assembly is secured to the door 14. Due to the design of the sector-like element as heretofore described, the door pivot 22 coincides substantially with the rotative center of the sector-like element when the same is attached to the door. The arm 26 extends back under and substantially parallel to the bottom of cabinet 10 when the door is in closed position and the dumbbell weight receptacle is suspended in substantially the plane of

the door. In other words, the center of the true arc of the sector-like element is substantially coincident with pivot 22 of the door 14.

Experiment has proved that with a balancing mechanism of this type associated with the damper door in the manner described the mechanism may be so adjusted that, under any conditions which may exist in the stack or atmosphere surrounding the boiler mechanism, a substantially constant predetermined draft may be maintained in the boiler. Operation and adjustment of the device may be described briefly in the following manner:

The dumbbell weight lying substantially in the plane of the damper door 14 may be regarded as the door assembly balancing weight. This is loaded with counterweights 60 until the door and sector assembly is perfectly balanced. This adjustment is one which should be made at the factory and in most instances should not be altered in the field. The weight piled up on the end of strap 90 may be called the draft balancing weight. Weights 60 are piled up at the end of the said strap until the damper door 14 takes the position corresponding to the desired draft in the fire box. This adjustment should be made when the boiler is in normal operation, the proper minimum draft being then readily ascertainable. The normal opening of the door may be altered by using more or less weights, according to whether a decrease or increase in said normal opening is desired. The weight positioned at the joinder of radial arm 26 with the arc of the sector may be regarded as the sector balancing weight and counterweights 60 should be added when the door 14 has a tendency to close too fast and slam against its frame under sudden and wide draft variations, or when the door is sluggish when moving from the closed position to its position under normal draft. Obviously the addition of weights here may necessitate readjustment of the draft balancing weight suspended by strap 90.

The weight 50, which is slidably mounted on swingable arm 38, is capable of universal movement within the peripheral confines of the sector-like element. This results from the fact that it follows the swinging movement of arm 38 and may be moved to any adjusted position along the said arm. It is immaterial whether or not this universally movable weight 50 be positioned within the plane of the sector-like element. It is used for making final adjustments when the addition or subtraction of a counterweight at the draft balancing weight position or the sector balancing weight position does not give the proper correction.

The hook 96 should preferably be within the reach of a boiler tender and is used for keeping the door 14 closed against the draft of the boiler when starting fires in coal fired boilers.

It will be apparent that the weight depending from strap 90 exerts a constant pull tending to close the door 14 regardless of the position in which the said door may be. This is true by reason of the fact that the rotative center of the sector-like element is substantially coincident with the pivot of the door and the torque arm through which the said weight operates is at all times equal to the radius of said arc. A perfect balance of the door and regulator mechanism attached thereto is obtained by variation of the weights positioned in the dumbbell receptacle which lies substantially in the plane of the door. The universally movable weight 50 permits an exceedingly fine adjustment of the door, poising

the same delicately upon its pivot at any opening of the door which proves most feasible for given draft conditions. Variation of the weights in the sector balancing weight will relieve any tendency toward too rapid movement of the door during varying draft conditions.

The function of such a draft regulator as that herein described of permitting opening and closing of the door in accordance with the need for air within the breeching or stack to maintain a constant draft is too well understood to require discussion herein. While the arms 24 and 26 do not constitute true radii of the true arc 28 of the sector, these arms are substantially radial and have been referred to in the claims as "radial arms." It is likewise true that in positioning the regulator mechanism on the door it may be impossible to make the center of the true arc coincide precisely with the pivot 22 of door 14. It will therefore be understood that an important feature of the design resides in the fact that the two are "substantially coincident." It will likewise be understood that the element which has been termed a "sector-like element" does not constitute a true sector in that the arms 24 and 26 are not true radii. The language of the claims is to be interpreted in the light of the explanations made herein. It is obviously unimportant whether a solid element having such a sector-like shape as the element illustrated is used in lieu of the latter, the important point being the geometrical arrangement of the assembly.

It is to be noted that the weights 60 and the various supports or receptacles therefor are so arranged that the said weights may be used interchangeably in any of the supports or receptacles.

Various modifications of the device illustrated herein will be apparent to those skilled in the art and for that reason I wish to limit myself only within the scope of the appended claims.

What I claim is:

1. A draft regulator including in combination a pivoted door, an element having a circular periphery of more than 180° and occupying a plane intersecting that of said door secured thereto substantially along a radius of said element so that its rotative center is substantially coincident with the door pivot, and a weight positioned on said element for universal movement in a single plane along the major portion of said circular periphery to permit its placement on either side of the plane of the door.

2. The combination with a draft regulator door arranged for swinging movement about a horizontal pivot, of a sector-like element having one radial arm secured to the face of said door so that the included arc is substantially concentric with said pivot, and a weight positioned on said element for universal movement within the peripheral limits of the sector.

3. The combination with a draft regulator door arranged for swinging movement about a horizontal pivot, of a sector-like element having one radial arm secured to the face of said door so that the included arc is substantially concentric with said pivot, a weight positioned on said element for universal movement within the peripheral limits of the sector, and means for fixing said weight at any adjusted position.

4. The combination with a draft regulator door arranged for swinging movement about a horizontal pivot, of a sector-like element having one radial arm secured to the face of said door so

that the included arc is substantially concentric with said pivot, the other radial arm extending in a direction substantially perpendicular to the plane of said door, fixed balancing weights positioned on said element on opposite sides of said pivot, and an adjustable weight positioned on said element for movement within the peripheral limits of said sector.

5. The combination with a draft regulator door arranged for inward swinging movement about a horizontal pivot, of a sector-like element having one radial arm secured to the face of said door and the other extending below said pivot to the inner side thereof, variable weights positioned on said element on opposite sides of said door, and a weight positioned on said element for adjusting movement within the peripheral limits of said element.

6. The combination with a draft regulator door arranged for inward swinging movement about a horizontal pivot, of a sector-like element having one radial arm secured to the face of said door and the other extending below said pivot to the inner side thereof, variable weights positioned on said element on opposite sides of said door, and a weight positioned on said element arranged for universal movement within the peripheral confines thereof.

7. The combination with a draft regulator door arranged for inward swinging movement about a horizontal pivot, of a sector-like element having one radial arm secured to the face of said door and the other extending below said pivot to the inner side thereof, variable weights positioned on said element on opposite sides of said door, an arm pivoted at one end adjacent the juncture of said radial arms and swingable at the other along the arc of the sector, and a weight slidable along said arm.

8. The combination with a draft regulator door arranged for inward swinging movement about a horizontal pivot, of a sector-like element having one radial arm secured to the face of said door and the other extending below said pivot to the inner side thereof, variable weights positioned on said element on opposite sides of said door, an arm pivoted at one end adjacent the juncture of said radial arms and swingable at the other along the arc of the sector, a weight slidable along said arm, means for fixing said arm at any point in its swinging movement, and means for fixing said weight at any point in its sliding movement.

9. The combination with a draft regulator door arranged for inward swinging movement about a horizontal pivot, of a sector-like element having one radial arm secured to the face of said door and the other extending below said pivot to the inner side thereof, a flexible strap secured to the outer face of the sector arc above a plane through said pivot perpendicular to said door and seated therealong, a variable weight supported on said strap, a variable weight positioned on said arc in substantially the plane of the door, a third variable weight positioned on said element inside the plane of the door, and a fourth weight positioned on said element for universal movement in a single plane within the external limits of the sector-like element.

10. A draft regulator including in combination a pivoted door at one edge, an element having a circular periphery and occupying a plane at right angles to said door secured thereto so that its rotative center is substantially coincident with the door pivot, variable weights fixedly positioned with reference to and on said element on oppo-

site sides of the plane of the door, and a weight positioned on said element for universal movement in a plane angular to that of the door and within the limiting confines of said circular periphery.

5 11. A draft regulator including in combination a pivoted door, an element having a circular periphery and occupying a plane at right angles to said door secured thereto so that its rotative center is substantially coincident with the door pivot, variable weights fixedly positioned with reference to and on said element on opposite sides of the plane of the door, a variable weight positioned on said element substantially in the plane 10 of the door, and a weight positioned on said element for universal movement in a plane angular to that of the door and within the limiting confines of said circular periphery.

15 12. Counterbalancing mechanism for a pivoted draft-regulating door comprising a pair of intersecting arms, a continuous member connecting the outer ends of said arms and extending throughout more than 180° to form a composite element, variable weights positioned on said element on opposite sides of one of said arms, a variable weight positioned on said continuous member and lying within a plane parallel to that of one of said arms, and a weight positioned between said arms and continuous member for universal movement in a plane substantially parallel 20 with that of said arms.

25 13. Counterbalancing mechanism for a pivoted draft-regulating door comprising a pair of intersecting arms connected at their outer extremities by a continuous member extending in excess of 30 180°, another arm pivoted adjacent the intersection of said arms and extending toward said continuous member, means at the other end of said last-mentioned arm whereby the same can be fixedly positioned at pre-determined points along said continuous member, and a weight slidable along said arm.

14. Counterbalancing mechanism for a pivoted draft-regulating door including a sector-like element, an arm slidably pivoted through a lost-motion connection adjacent the juncture of the radial arms of said element and slidably engaged with the periphery thereof, and a weight slidably mounted on said arm.

5 15. Counterbalancing mechanism for a pivoted draft-regulating door including a sector-like element, an arm pivoted adjacent the juncture of the radial arms of said element and slidably engaged with the periphery thereof, and a weight slidably mounted on said arm.

10 16. Counterbalancing mechanism for a pivoted draft-regulating door including a sector-like element, an arm pivoted adjacent the juncture of the radial arms of said element and slidably engaged with the periphery thereof, a weight slidably mounted on said arm, a weight fixedly positioned on said element adjacent the juncture of 15 one radial arm and the arc thereof, a second weight fixedly positioned on said element in a plane parallel to the other radial arm, and a weight secured to the arc of said sector at a point removed substantially 180° from said juncture- 20 located weight.

25 17. Counterbalancing mechanism for a pivoted draft-regulating door including a sector-like element, an arm pivoted adjacent the juncture of the radial arms of said element and slidably engaged with the periphery thereof, a weight slidably mounted on said arm, a weight fixedly positioned on said element adjacent the juncture of one radial arm and the arc thereof, a second weight fixedly positioned on said element in a 30 plane parallel to the other radial arm, a flexible strap secured to the arc of said sector at a point removed substantially 180° from said juncture- 35 located weight, and a variable weight secured to said strap.
